1 INTERNAL COMBUSTION ENGINE

TECHNICAL FIELD

The present invention relates to an internal combustion engine for use on a saddle-type vehicle, and more particularly to an internal combustion engine provided with a valve train or variable valve operating apparatus.

BACKGROUND ART

There have been known variable valve operating apparatuses for use in internal combustion engines, including a cam switching mechanism in which a cam carrier has a plurality of cam lobes formed on the outer circumferential surface thereof and having different cam profiles that determine valve operating characteristics. The cam carrier is relatively non-rotatably and axially slidably fitted over a camshaft, and is axially moved to cause different cam lobes to act on engine valves to switch the valve operating characteristics (see, for example, Patent Document 1).

PRIOR ART DOCUMENT

Patent Document

[Patent Document 1]
JP 2014-134165 A

According to the variable valve operating apparatus disclosed in Patent Document 1, the cam carrier that is slidably fitted over the camshaft rotatably supported in the cylinder head has a guide groove (lead groove) defined fully circumferentially therein, and switching pins engage in the guide groove to guide and move the cam carrier axially while the cam carrier is rotating, to thereby switch cam lobes that operate the engine valves.

In the cam switching mechanism of the valve operating apparatus disclosed, the guide groove is defined between a pair of side wall surfaces that face each other and serve individually as first and second switching cams, and the switching pins include first and second switching pins for contact with the first and second switching cams, respectively. When the first switching pin projects into contact with the first switching cam, it axially moves the cam carrier into a first position in which a first cam lobe acts on an engine valve, and when the second switching pin projects into contact with the second switching cam, it axially moves the cam carrier into a second position in which a second cam lobe acts on the engine valve.

Therefore, the valve operating apparatus includes a hydraulic pressure circuit for applying hydraulic pressure to respective ends of the first and second switching pins to move the first and second switching pins alternately back and forth, i.e., to advance and retract the first and second switching pins alternately.

The first switching pin is movably disposed in a pin slot whose upper portion is held in fluid communication with a first oil channel that is held in fluid communication with an axially elongate first oil gallery. Similarly, the second switching pin is movably disposed in a pin slot whose upper portion is held in fluid communication with a second oil channel that is held in fluid communication with an axially elongate second oil gallery.

SUMMARY OF THE INVENTION

Problems to be Solved by the Invention

Since the cam switching mechanism disclosed in Patent Document 1 actuates the first and second switching pins by

2

applying oil pressure thereto, the oil circuit including the pin slots, the oil channels, the oil galleries, etc. needs to be positioned near the first and second switching pins. According to Patent Document 1, the oil or hydraulic pressure circuit is formed in a cylinder head cover positioned above the cam carrier.

Therefore, it is necessary to form complex structural details of the oil or hydraulic pressure circuit in the cylinder head cover. In order to form the hydraulic pressure circuit in the cylinder head cover, the cylinder head cover needs to be large in size, making the internal combustion engine large in size.

Patent Document 1 is silent about where to place an electromagnetic valve (solenoid valve) for switching the supply of hydraulic pressure to and the discharge of hydraulic pressure from the oil galleries.

Saddle-type vehicles have a limited space available thereon for installing an internal combustion engine. Particularly, saddle-type vehicles have a limited width in their leftward and rightward directions near the cylinder head and the cylinder head cover of the engine installed thereon, and include intake and exhaust components and other parts disposed forward and rearward of the cylinder head and the cylinder head cover. It is difficult to place the solenoid valve out of interference with peripheral parts of the internal combustion engine, in the vicinity of the oil galleries in the cylinder head cover in order to shorten oil channels.

If the peripheral parts are placed remote from the internal combustion engine so that they do not interfere with the solenoid valve, then the vehicle tends to be large in size.

The present invention has been made in view of the above problems. It is an object of the present invention to provide an internal combustion engine provided with a variable valve operating apparatus, for use on a saddle-type vehicle, which includes a solenoid valve placed at an appropriate location in a cylinder head out of interference with peripheral parts of the internal combustion engine, for thereby making the vehicle small in size.

Means for Solving the Problems

In order to achieve the above object, there is provided in accordance with the present invention an internal combustion engine for use on a saddle-type vehicle, including a cylinder block and a cylinder head stacked on and integrally fastened to a crankcase, the internal combustion engine having a variable valve operating apparatus comprising: a camshaft rotatably mounted in the cylinder head and oriented in leftward and rightward directions across a vehicle width; a cam carrier in the form of a hollow cylindrical member relatively non-rotatably and axially slidably fitted over the camshaft, the cam carrier including, on an outer circumferential surface thereof, a plurality of cam lobes having different cam profiles and disposed axially adjacent to each other; and a cam switching mechanism for axially moving the cam carrier to switch the cam lobes to act on an engine valve;

wherein the cam switching mechanism includes: a lead groove formed in an outer circumferential surface of the cam carrier and extending fully circumferentially therearound; a switching pin capable of being advanced to engage in and retracted to disengage from the lead groove; a switching drive shaft disposed parallel to the camshaft to be movable longitudinally thereof so as to cooperate with the switching pin to constitute a cam mechanism for advancing and retracting movements of the switching pin, in such a manner that the advancing movement causes the switching pin to

engage in the lead groove so as to axially move the cam carrier while rotating, to switch the cam lobes to act on the engine valve; a hydraulic pressure actuator for longitudinally moving the switching drive shaft; and a solenoid valve for switching hydraulic pressure acting on the hydraulic pressure actuator, the solenoid valve being positioned on one of left and right ends in the leftward and rightward directions across the vehicle width, of one of front and rear surfaces of the cylinder head.

With the above arrangement, since the solenoid valve is disposed on the front surface or rear surface of the cylinder head, the solenoid valve does not protrude laterally in the leftward and rightward directions of the cylinder head, thereby preventing the internal combustion engine from increasing its width in the leftward and rightward directions.

Furthermore, as the solenoid valve is mounted on the left end or right end in the leftward and rightward directions across the vehicle width of the front surface or rear surface of the cylinder head, peripheral parts of the internal combustion engine can be placed closely to the front surface or rear surface of the cylinder head, using a wide central space, except the solenoid valve, on the front surface or rear surface of the cylinder head. The peripheral area of the internal combustion engine is thus rendered compact, reducing the length of the vehicle in the forward and rearward directions to make the vehicle small in size.

Moreover, because the solenoid valve is provided on the cylinder head, the hydraulic pressure channels that provide fluid communication with the hydraulic pressure actuator can be short.

In the above arrangement, the solenoid valve may be disposed on the front surface of the cylinder head.

With the above arrangement, since the solenoid valve is disposed on the left end or right end of the front surface of the cylinder head, various devices disposed rearward of the cylinder head can easily be placed within the width of the cylinder head in the leftward and rightward directions, and the peripheral parts of the engine, which are disposed forward of the cylinder head, can be placed closely to the front surface of the cylinder head, using a wide central space, except the solenoid valve, on the front surface of the cylinder head. The peripheral area of the internal combustion engine is further rendered compact, reducing the length of the vehicle in the forward and rearward directions to make the vehicle small in size.

In the above arrangement, the hydraulic pressure actuator may be integrally formed with the cylinder head; the cylinder head may include a mating surface having openings of hydraulic pressure channels defined therein; and the solenoid valve may have a mating surface with openings of hydraulic pressure ports defined therein, the mating surface of the solenoid valve mating with the mating surface of the cylinder head, so that the solenoid valve is mounted on the cylinder head.

With the above arrangement, the hydraulic pressure actuator is integrally formed with the cylinder head, and the mating surface of the solenoid valve which has the openings of the fluid pressure ports defined therein mates with the mating surface of the cylinder head which has the openings of the hydraulic pressure channels defined therein, so that the solenoid valve is mounted on the cylinder head. The hydraulic pressure channels in the solenoid valve and the hydraulic pressure channels in the cylinder head are directly coupled to each other, and hence can be short without the need for separate joint pipes.

In the above arrangement, the solenoid valve may include an electromagnetic solenoid having a plunger and a spool

valve operable with the plunger, the solenoid valve being mounted on the cylinder head in such a posture that the plunger is linearly movable together with the spool valve in directions perpendicular to axial directions of a cylinder defined in the cylinder block.

With this arrangement, since the directions in which the plunger and the spool valve of the electromagnetic solenoid are moved are perpendicular to the axial directions of the cylinder, the solenoid valve is not susceptible to vibrations caused by the internal combustion engine while in operation, and can operate in an exact manner.

In the above arrangement, the hydraulic pressure actuator is preferably mounted on one of left and right ends of the switching drive shaft; and the solenoid valve is preferably disposed on the same side in the leftward and rightward directions across the vehicle width as the hydraulic pressure actuator.

With the above arrangement, the hydraulic pressure actuator is provided on the left end or right end of the switching drive shaft, and the solenoid valve is disposed on the same side in the leftward and rightward directions across the vehicle width as the hydraulic pressure actuator. Consequently, the solenoid valve and the hydraulic pressure actuator can be disposed closely to each other, thereby shortening hydraulic pressure channels that provide fluid communication between the solenoid valve and the hydraulic pressure actuator, so that the internal combustion engine is prevented from being large in size.

In the above arrangement, the camshaft is preferably rotatable by drive power transmitted from the internal combustion engine through a cam chain; and the solenoid valve is preferably disposed opposite a cam chain compartment housing the cam chain therein, in axial directions of the camshaft.

With the above arrangement, the solenoid valve is disposed opposite the cam chain compartment housing the cam chain therein in the axial directions of the camshaft. Therefore, the solenoid valve is prevented from further protruding on the side wall where the cam chain compartment is defined. Consequently, the internal combustion engine is prevented from being large in size.

In the above arrangement, the cylinder head may be separable in axial directions of the cylinder in the cylinder block into a first cylinder head member mounted on the cylinder block and a second cylinder head member mounted on the first cylinder head member; the valves may be supported on the first cylinder head member; the second cylinder head member may have bearings by which the camshaft is rotatably supported, the hydraulic pressure actuator being supported on the second cylinder head member; and the solenoid valve may be provided in the second cylinder head member.

With this arrangement, the cylinder head is separable in the axial directions of the cylinder in the cylinder block into the first cylinder head member mounted on the cylinder block and the second cylinder head member mounted on the first cylinder head member, the valves are supported on the first cylinder head member, the second cylinder head member has the bearings by which the camshaft is rotatably supported, the hydraulic pressure actuator being supported on the second cylinder head member, and the solenoid valve is provided in the second cylinder head member. Therefore, the camshaft, the cam switching mechanism, and the hydraulic pressure actuator, other than the valves that are supported on the first cylinder head member, are provided on the separate second cylinder head member. The first and second cylinder head members are thus simplified in struc-

ture, and can be manufactured with ease. Furthermore, as the solenoid valve is provided in the second cylinder head member, the hydraulic pressure channels that provide fluid communication between the solenoid valve and the hydraulic pressure actuator can be short and constructed with ease.

In the above arrangement, the internal combustion engine may further comprise a radiator shaped to curve to project rearward and disposed along a front surface of the cylinder head; and the solenoid valve and the radiator are preferably partly superposed on each other as viewed in side elevation in widthwise directions of the saddle-type vehicle.

With the above arrangement, the radiator which is curved to project rearward is disposed along the front surface of the cylinder head, and the solenoid valve and the radiator are disposed so as to be partly superposed on each other as viewed in side elevation in the widthwise directions of the vehicle. Consequently, the radiator that is curved to project rearward can be placed as closely to the cylinder head as possible out of interference with the solenoid valve mounted on the left end or right end of the front surface of the cylinder head. The radiator and the internal combustion engine that are disposed in front and rear positions can be disposed in a compact layout, making it possible to minimize the length of the vehicle in the forward and rearward directions.

Effects of the Invention

According to the present invention, since the solenoid valve is disposed on the front surface or rear surface of the cylinder head, the solenoid valve does not protrude laterally in the leftward and rightward directions of the cylinder head, thereby preventing the internal combustion engine from increasing in its width in the leftward and rightward directions.

Furthermore, as the solenoid valve is mounted on the left end or right end in the leftward and rightward directions across the vehicle width of the front surface or rear surface of the cylinder head, the peripheral parts of the internal combustion engine can be placed closely to the front surface or rear surface of the cylinder head, using a wide central space, except the solenoid valve, on the front surface or rear surface of the cylinder head. The peripheral area of the internal combustion engine is thus rendered compact, reducing the length of the vehicle in the forward and rearward directions to make the vehicle small in size.

Moreover, because the solenoid valve is provided on the cylinder head, the hydraulic pressure channels that provide fluid communication with the hydraulic pressure actuator can be shortened.

BRIEF DESCRIPTION OF THE DRAWINGS

FIG. 1 is a side elevational view of a motorcycle on which is mounted an internal combustion engine according to an embodiment of the present invention;

FIG. 2 is a left-hand side elevational view depicting positional relationship between the internal combustion engine and a radiator;

FIG. 3 is a plan view depicting the positional relationship between the internal combustion engine and the radiator;

FIG. 4 is a left-hand side elevational view of a valve operating mechanism of the variable valve operating apparatus, indicating profiles of a cylinder head cover, etc. of the internal combustion engine by two-dot-and-dash lines;

FIG. 5 is a plan view of an upper cylinder head member with the cylinder head cover omitted from illustration;

FIG. 6 is a perspective view of major parts of an intake cam switching mechanism and an exhaust cam switching mechanism that are partly omitted from illustration;

FIG. 7 is a perspective view of a first switching pin and a second switching pin that are combined with an intake switching drive shaft;

FIG. 8 is a sectional view depicting a manner in which oil under pressure is supplied to and discharged from an intake hydraulic pressure actuator and an exhaust hydraulic pressure actuator at the time a linear solenoid valve is not actuated;

FIG. 9 is a sectional view depicting a manner in which oil under pressure is supplied to and discharged from the intake hydraulic pressure actuator and the exhaust hydraulic pressure actuator at the time the linear solenoid valve is actuated;

FIG. 10 is a front elevational view of a left end mating surface of a front face of a front wall of the upper cylinder head member;

FIG. 11 is a perspective view of the linear solenoid valve;

FIG. 12 is an elevational view depicting a manner in which major parts of the intake cam switching mechanism operate at the time the internal combustion engine operates in a low-speed range; and

FIG. 13 is an elevational view depicting a manner in which the major parts of the intake cam switching mechanism operate at the time the internal combustion engine operates in a high-speed range.

MODE FOR CARRYING OUT THE INVENTION

A motorcycle 100 as a saddle-type vehicle having mounted thereon an internal combustion engine according to an embodiment of the present invention will be described below with reference to the drawings.

FIG. 1 is a side elevational view of the motorcycle 100 as a saddle-type vehicle that includes an internal combustion engine, incorporating therein the variable valve operating apparatus, according to the embodiment of the present invention.

In the present description and the claims, directions such as forward, rearward, leftward, and rightward and other similar directional expressions are in accordance with ordinary directional standards on the motorcycle 100 according to the present embodiment where the direction in which the motorcycle 100 moves straight ahead is referred to as the forward direction. In the accompanying drawings, FR represents the forward direction, RR the rearward direction, LH the leftward direction, and RH the rightward direction.

The motorcycle 100 has a vehicle body frame including a head pipe 102 by which there is steerable supported a front fork 105 with a front wheel 106 rotatably supported thereon by a front axle, and a pair of left and right main frames 103 extending rearward and obliquely downward from the head pipe 102.

The main frames 103 have front portions from which engine hangers 103a are suspended downward and rear portions bent downward from which pivot frames 103b extend downward.

Seat rails 104 are coupled to and extend rearward from respective central rear portions of the main frames 103.

A swing arm 108 extends rearward from a front end thereof that is pivotally supported on the pivot frames 103b by a pivot shaft 107, and has a rear end on which a rear wheel 109 is rotatably supported by a rear axle.

A link mechanism 110 is provided between the swing arm 108 and the pivot frames 103b, and a rear cushion 111 is interposed between part of the link mechanism 110 and the seat rails 104.

A power unit Pu is suspended between the engine hangers 103a and the pivot frames 103b of the main frames 103. The power unit Pu includes a transmission M in its rear part which has a countershaft 12 that serves as an output shaft. A drive chain 114 is trained around a drive sprocket 112 fitted over the output shaft of the transmission M and a driven sprocket 113 fitted over the rear axle by which the rear wheel 109 is supported.

The motorcycle 100 includes an air cleaner 122 mounted on front portions of the main frames 103 and a fuel tank 116 mounted on rear portions of the main frames 103. A main seat 117 and a pillion seat 118 are supported on the seat rails 104 behind the fuel tank 116.

The power unit Pu also includes an internal combustion engine E in its front part which includes an in-line four-cylinder water-cooled four-stroke internal combustion engine with its crankshaft 10 extending laterally. The internal combustion engine E is mounted on the vehicle body frame with its cylinders tilted forward at an appropriate angle.

The crankshaft 10 of the internal combustion engine E is oriented widthwise across the vehicle body frame along leftward and rightward directions, and is rotatably supported by a crankcase 1. The transmission M is integrally combined with the crankcase 1 behind the crankshaft 10.

As shown in FIG. 2, the internal combustion engine E includes an engine body including a cylinder block 2 over the crankcase 1 and having four cylinders disposed in line therein, a cylinder head 3 coupled to an upper portion of the cylinder block 2 with a gasket interposed therebetween, and a cylinder head cover 4 covering an upper portion of the cylinder head 3.

The cylinders in the cylinder block 2 have respective cylinder bores defined therein in which respective pistons are slidably disposed. The cylinder bores have respective central axes as cylinder axes Lc that are tilted forward. The cylinder block 2, the cylinder head 3, and the cylinder head cover 4 are successively stacked on and extend upward from the crankcase 1 in a slightly forwardly tilted orientation.

An oil pan 5 is mounted on the lower end of the crankcase 1 and projects downward therefrom.

A radiator 130 is in a curved shape to protrude rearward as depicted in plan in FIG. 3 and disposed closely in front of the engine body of the internal combustion engine E.

As depicted in FIGS. 1 through 3, the radiator 130 is tilted forward along a front surface of the engine body that is tilted slightly forward.

Left and right radiator fans 131 are disposed behind the radiator 130.

The crankcase 1 is of a vertically separable structure including an upper crankcase member 1U and a lower crankcase member 1L that have respective mating surfaces coupled to each other, with the crankshaft 10 being rotatably supported between the mating surfaces.

As shown in FIG. 2, the transmission M is housed in the crankcase 1 behind the crankshaft 10. The transmission M has a main shaft 11 in addition to the countershaft 12, and the main shaft 11 and the countershaft 12 are oriented widthwise across the vehicle body parallel to the crankshaft 10 and rotatably supported by the crankcase 1.

The crankcase 1 has a transmission chamber defined therein in which the main shaft 11 and the countershaft 12 are disposed horizontally in the leftward and rightward

directions parallel to the crankshaft 10 (see FIG. 3). The countershaft 12 extends to the left through the crankcase 1 and serves as the output shaft of the transmission M.

As shown in FIG. 1, intake pipes that are associated with the respective cylinders extend from a rear side surface of the cylinder head 23 and are connected to the air cleaner 122 through a throttle body 121.

Exhaust pipes 125 that are associated with the respective cylinders extend downward from a front side surface of the cylinder head 23 and are bent downward and then extend rearward on the right side of the oil pan 5.

As shown in FIG. 4, the internal combustion engine E also includes a four-valve DOHC variable valve operating apparatus 40 disposed in the cylinder head 3.

The cylinder head 3 in the internal combustion engine E, which is vertically separable along the cylinder axes Lc, includes a lower cylinder head member (first cylinder head member) 3L mounted on the cylinder block 2 and an upper cylinder head member (second cylinder head member) 3U mounted on the lower cylinder head member 3L (see FIGS. 2 and 4).

As depicted in FIG. 4, the lower cylinder head member 3L includes two intake ports 31i curved rearward and extending upward from a combustion chamber 30 in each of the cylinders, and two exhaust ports 31e curved forward and extending from the combustion chamber 30 in each of the cylinders.

The intake ports 31i have respective intake valve holes that are open into the combustion chamber 30, and the exhaust ports 31e have respective exhaust valve holes that are open into the combustion chamber 30. Two left and right intake valves 41 and two left and right exhaust valves 51 for selectively opening and closing the intake valve holes and the exhaust valve holes are slidably supported in the lower cylinder head member 3L for back-and-forth sliding movement in synchronism with rotation of the crankshaft 10.

The lower cylinder head member 3L and the cylinder block 2 are integrally fastened to the upper crankcase member 1U by stud bolts 7 (see FIGS. 4 and 5).

The upper cylinder head member 3U that is mounted on the lower cylinder head member 3L includes a rectangular frame wall assembly which includes, as depicted in FIG. 5, a front side wall 3Fr that is elongated in the leftward and rightward directions, a rear side wall 3Rr that is elongated in the leftward and rightward directions, a left side wall 3Lh that is shorter than the front and rear side walls 3Fr and 3Rr in the forward and rearward directions, and a right side wall 3Rh that is shorter than the front and rear side walls 3Fr and 3Rr in the forward and rearward directions.

The inside space of the rectangular frame wall assembly of the upper cylinder head member 3U is divided into a right narrow cam chain compartment 3c and a left valve operating compartment 3d by a bearing wall 3vr extending parallel to the right side wall 3Rh. The valve operating compartment 3d is subdivided into five compartments by four bearing walls 3v extending parallel to the left and right side walls 3Lh and 3Rh.

The bearing walls 3v are positioned individually above the centers of the combustion chambers 30 in the cylinders, and have plug insertion tubes 3vp, individually, on their central areas in the forward and rearward directions for insertion of respective spark plugs therein.

The variable valve operating apparatus 40 is housed in the valve operating compartment 3d that is defined by the cylinder head 3 and the cylinder head cover 4.

As depicted in FIGS. 4 and 5, the left and right intake valves 41 that are associated with each of the in-line four

cylinders are provided in four pairs in a straight array along the leftward and rightward directions. A single intake camshaft 42 that is oriented in the leftward and rightward directions is disposed in the valve operating compartment 3d above the four pairs of the intake valves 41. The intake camshaft 42 is fitted in semi-arcuate bearings 3vv in the bearing walls 3v and 3vr of the upper cylinder head member 3U and sandwiched and rotatably supported by a camshaft holder 33.

Similarly, the left and right exhaust valves 51 that are associated with each of the in-line four cylinders are provided in four pairs in a straight array along the leftward and rightward directions. A single exhaust camshaft 52 that is oriented in the leftward and rightward directions is disposed in the valve operating compartment 3d above the four pairs of the exhaust valves 51. The exhaust camshaft 52 is fitted in semi-arcuate bearings 3vv in the bearing walls 3v and 3vr of the upper cylinder head member 3U and sandwiched and rotatably supported by the camshaft holder 33.

The exhaust camshaft 52 is disposed forward of and parallel to the intake camshaft 42.

As depicted in FIG. 5, the intake camshaft 42 includes a journal 42a near its right end that is rotatably supported on the bearing wall 3vr and is axially positioned by flanges formed on both sides of the journal 42a and sandwiching the bearing wall 3vr therebetween. The intake camshaft 42 also includes an elongate splined shank 42b having external splines on its outer circumferential surface and extending leftward from the journal 42a through the four bearing walls 3v in the valve operating compartment 3d.

An intake driven gear 47 is fitted over the flange on the right end of the intake camshaft 42 which projects into the cam chain compartment 3c.

Likewise, the exhaust camshaft 52 includes a journal 52a near its right end that is rotatably supported by the bearing wall 3vr and is axially positioned by flanges formed on both sides of the journal 52a and sandwiching the bearing wall 3vr therebetween. The exhaust camshaft 52 also includes an elongate splined shank 52b having external splines on its outer circumferential surface and extending leftward from the journal 52a through the four bearing walls 3v in the valve operating compartment 3d.

An exhaust driven gear 57 is fitted over the flange on the right end of the exhaust camshaft 52 which projects into the cam chain compartment 3c.

Four intake cam carriers 43 in the form of hollow cylindrical members are arrayed on and splined to the splined shank 42b of the intake camshaft 42.

The four intake cam carriers 43 are relatively non-rotatably and axially slidably fitted over the intake camshaft 42.

Similarly, four exhaust cam carriers 53 in the form of hollow cylindrical members are arrayed on and splined to the splined shank 52b of the exhaust camshaft 52, and are relatively non-rotatably and axially slidably fitted over the exhaust camshaft 52.

FIG. 6 is a perspective view of major parts of an intake cam switching mechanism and an exhaust cam switching mechanism that are partly omitted from illustration.

As depicted in FIGS. 5 and 6, each of the intake cam carriers 43 includes, on its outer circumferential surface, two left and right sets of a high-speed cam lobe 43A of a larger lobe lift and a low-speed cam lobe 43B of a smaller lobe lift which have different cam profiles, individually, and are disposed axially adjacent to each other, and a tubular journal 43C having a predetermined axial length that is interposed between the two left and right sets of the high-speed cam lobe 43A and the low-speed cam lobe 43B.

The high-speed cam lobe 43A and the low-speed cam lobe 43B that are disposed axially adjacent to each other have respective cam profile base circles whose outside diameters are identical to each other, and are disposed in respective identical angular positions (see FIGS. 4 and 5).

Each of the intake cam carriers 43 also includes a lead groove tube 43D disposed axially on the right side of the high-speed cam lobe 43A of the right set and having lead grooves 44 defined in an outer circumferential surface thereof and extending fully circumferentially therearound.

The lead groove tube 43D has an outside diameter slightly smaller than the identical outside diameter of the base circles of the high-speed cam lobe 43A and the low-speed cam lobe 43B.

The lead grooves 44 in the lead groove tube 43D include an annular lead groove 44c defined fully circumferentially on the lead groove tube 43D at a predetermined axial position thereon, and a right shift lead groove 44r and a left shift lead groove 44l that are branched leftward and rightward spirally from the annular lead groove 44c and spaced axially therefrom by respective predetermined distances (see FIG. 5).

The four intake cam carriers 43 thus constructed are arrayed on and splined to the splined shank 42b of the intake camshaft 42 at predetermined axially spaced intervals therebetween.

As depicted in FIG. 5, the intake camshaft 42 with the four intake cam carriers 43 arrayed thereon is rotatably supported by rear bearings 3vv on the bearing wall 3vr and the four bearing walls 3v of the upper cylinder head member 3U.

The journal 42a of the intake camshaft 42 is rotatably supported on the bearing wall 3vr and the tubular journals 43C of the respective intake cam carriers 43 are rotatably supported on the respective bearing walls 3v.

Similarly to the intake cam carriers 43, each of the exhaust cam carriers 53 that are splined to the splined shank 52b of the exhaust camshaft 52 includes, on its outer circumferential surface, two left and right sets of a high-speed cam lobe 53A of a larger lobe lift and a low-speed cam lobe 53B of a smaller lobe lift which have different cam profiles, individually, and are disposed axially adjacent to each other, and a tubular journal 53C having a predetermined axial length that is interposed between the two left and right sets of the high-speed cam lobe 53A and the low-speed cam lobe 53B. Each of the exhaust cam carriers 53 also includes a lead groove tube 53D disposed axially on the right side of the high-speed cam lobe 53A of the right set and having lead grooves 54 defined in an outer circumferential surface thereof and extending fully circumferentially therearound.

The lead grooves 54 in the lead groove tube 53D include an annular lead groove 54c defined fully circumferentially on the lead groove tube 53D at a predetermined axial position thereon, and a right shift lead groove 54r and a left shift lead groove 54l that are branched leftward and rightward spirally from the annular lead groove 54c and spaced axially therefrom by respective predetermined distances (see FIG. 5).

The four exhaust cam carriers 53 thus constructed are arrayed on and splined to the splined shank 52b of the exhaust camshaft 52 at predetermined axially spaced intervals therebetween. As depicted in FIG. 5, the exhaust camshaft 52 with the four exhaust cam carriers 53 arrayed thereon is rotatably supported by front bearings 3vv on the bearing walls 3v and 3vr of the upper cylinder head member 3U.

11

The journal 52a of the exhaust camshaft 52 is rotatably supported on the bearing wall 3vr and the tubular journals 53C of the respective exhaust cam carriers 53 are rotatably supported on the respective bearing walls 3v.

When the intake camshaft 42 (and the intake cam carriers 43) and the exhaust camshaft 52 (and the exhaust cam carriers 53) are supported on the bearing wall 3vr and the four bearing walls 3v of the upper cylinder head member 3U, the intake camshaft 42 (and the intake cam carriers 43) and the exhaust camshaft 52 (and the exhaust cam carriers 53) are sandwiched and rotatably supported by the camshaft holder 33 (see FIG. 4) that is placed over the bearing wall 3vr and the four bearing walls 3v.

Specifically, the four intake cam carriers 43 are co-rotatably and axially slidably supported on the intake camshaft 42, and the four exhaust cam carriers 53 are also co-rotatably and axially slidably supported on the exhaust camshaft 52.

The intake driven gear 47 mounted on the right end of the intake camshaft 42 and the exhaust driven gear 57 mounted on the right end of the exhaust camshaft 52 are of the same diameter and are placed side by side individually in rear and front positions in the cam chain compartment 3c. As shown in FIG. 4, a large-diameter idle gear 61 that is held in mesh with the intake driven gear 47 and the exhaust driven gear 57 is rotatably supported below the space therebetween.

As depicted in FIGS. 4 and 5, an idle chain sprocket 62 that is coaxial with the idle gear 61 is provided integrally with the idle gear 61 for rotation therewith. A cam chain 66 is trained around the idle chain sprocket 62 and a small-diameter chain sprocket, not depicted, fitted over the crankshaft 10 that is disposed below the idle chain sprocket 62.

When rotation of the crankshaft 10 is transmitted through the cam chain 66 to the idle chain sprocket 62, the idle gear 61 that is combined integrally with the idle chain sprocket 62 rotates, rotating the intake driven gear 47 and the exhaust driven gear 57 that are held in mesh with the idle gear 61. Therefore, the intake driven gear 47 rotates the intake camshaft 42 about its own axis, whereas the exhaust driven gear 57 rotates the exhaust camshaft 52 about its own axis.

As depicted in FIG. 6, an intake cam switching mechanism 70 includes an intake switching drive shaft 71 disposed obliquely forward and downward of and extending parallel to the intake camshaft 42, and an exhaust cam switching mechanism 80 includes an exhaust switching drive shaft 81 disposed obliquely forward and downward of and extending parallel to the exhaust camshaft 52.

The intake switching drive shaft 71 and the exhaust switching drive shaft 81 are supported on the upper cylinder head member 3U.

As depicted in FIGS. 5 and 12, the upper cylinder head member 3U houses therein a tubular rod 3A oriented in the leftward and rightward directions in the valve operating compartment 3d and extending straight through the bearing wall 3vr and the four bearing walls 3v at a position slightly rearward from the center of the valve operating compartment 3d.

Likewise, as shown in FIG. 5, the upper cylinder head member 3U also houses therein a tubular rod 3B oriented in the leftward and rightward directions in the valve operating compartment 3d and extending through the bearing wall 3vr and the four bearing walls 3v straight on an inner surface of the front side wall 3Fr of the valve operating compartment 3d.

The tubular rod 3A has an axial hole defined therein through which the intake switching drive shaft 71 is axially slidably fitted, and the tubular rod 3B has an axial hole

12

defined therein through which the exhaust switching drive shaft 81 is axially slidably fitted.

The tubular rod 3A has two spaces or gaps defined therein at respective positions, corresponding individually to the left and right intake valves 41, on both sides of each of the bearing walls 3v, thereby exposing portions of the intake switching drive shaft 71. Intake rocker arms 72 are swingably supported on the exposed portions of the intake switching drive shaft 71 (see FIGS. 5 and 12).

In other words, the intake switching drive shaft 71 doubles as a rocker arm shaft.

As depicted in FIGS. 4 and 6, each of the intake rocker arms 72 has a distal end held in abutment against the upper end of one of the intake valves 41 and an upper curved end surface held in sliding contact with the high-speed cam lobe 43A or the low-speed cam lobe 43B of one of the sets dependent on axial movement of the corresponding intake cam carrier 43.

Therefore, when the intake cam carrier 43 rotates about its own axis, the high-speed cam lobe 43A or the low-speed cam lobe 43B swings the intake rocker arm 72 according to the cam profile thereof, depressing the intake valve 41 to open the corresponding intake valve hole into the combustion chamber 30.

Similarly, the tubular rod 3B has two spaces or gaps defined therein at respective positions, corresponding individually to the left and right exhaust valves 51, on both sides of each of the bearing walls 3v, thereby exposing portions of the exhaust switching drive shaft 81. Exhaust rocker arms 82 are swingably supported on the exposed portions of the exhaust switching drive shaft 81 (see FIGS. 5 and 6).

In other words, the exhaust switching drive shaft 81 doubles as a rocker arm shaft.

As depicted in FIGS. 4 and 6, each of the exhaust rocker arms 82 has a distal end held in abutment against the upper end of one of the exhaust valves 51 and has an upper curved end surface held in sliding contact with the high-speed cam lobe 53A or the low-speed cam lobe 53B of one of the sets, dependent on axial movement of the corresponding exhaust cam carrier 53.

Therefore, when the exhaust cam carrier 53 rotates about its own axis, the high-speed cam lobe 53A or the low-speed cam lobe 53B swings the exhaust rocker arm 82 according to the cam profile thereof, depressing the exhaust valve 51 to open the corresponding exhaust valve hole into the combustion chamber 30.

Referring to FIG. 12, the tubular rod 3A has thereon two left and right cylindrical bosses 3As that are adjacent to each other in the leftward and rightward directions. The cylindrical bosses 3As are disposed at respective positions corresponding to and projecting toward the lead groove tube 43D of each of the intake cam carriers 43.

The cylindrical bosses 3As have respective bores defined therein which extend through the tubular rod 3A.

A first switching pin 73 and a second switching pin 74 are slidably fitted individually in the bores in the left and right cylindrical bosses 3As.

As depicted in FIG. 7, the first switching pin 73 includes a distal cylindrical column 73a, a proximal cylindrical column 73b, and an intermediate joint bar 73c interconnecting the distal cylindrical column 73a and the proximal cylindrical column 73b coaxially in line with each other.

The proximal cylindrical column 73b is smaller in outside diameter than the distal cylindrical column 73a.

The distal cylindrical column 73a includes a reduced-diameter engaging end 73ae projecting axially in a direction away from the proximal cylindrical column 73b.

The proximal cylindrical column 73b has a conical end face 73bt that faces and is joined to the intermediate joint bar 73c.

The second switching pin 74 is of a shape identical to the first switching pin 73, and includes a distal cylindrical column 74a, a proximal cylindrical column 74b, and an intermediate joint bar 74c interconnecting the distal cylindrical column 74a and the proximal cylindrical column 74b coaxially in line with each other.

As depicted in FIG. 7, the intake switching drive shaft 71 has an elongate hole 71a defined axially centrally therethrough.

The elongate hole 71a has a width slightly larger than the diameter of the intermediate joint bar 73c of the first switching pin 73, but smaller than the diameter of the proximal cylindrical column 73b.

The intake switching drive shaft 71 also has a cam surface 71C on an open end face of the elongate hole 71a. The cam surface 71C includes two left recessed faces 71Cv and two right recessed faces 71Cv that are disposed successively in the leftward and rightward directions with flat faces 71Cp interposed therebetween.

The first switching pin 73 is installed on the intake switching drive shaft 71 such that the intermediate joint bar 73c thereof extends diametrically through the elongate hole 71a in the intake switching drive shaft 71. The first switching pin 73 is normally biased by a helical spring 75 to press the conical end face 73bt of the proximal cylindrical column 73b against the cam surface 71C on the open end face of the elongate hole 71a in the intake switching drive shaft 71. When the intake switching drive shaft 71 moves axially, the cam surface 71C moves in sliding contact with the conical end face 73bt of the proximal cylindrical column 73b of the first switching pin 73, which is kept in a fixed position with respect to the axial directions of the intake switching drive shaft 71 and is slideable in directions perpendicularly to the axial directions of the intake switching drive shaft 71. Therefore, the intake switching drive shaft 71 and the first switching pin 73 (and also the second switching pin 74) jointly make up a linear-motion cam mechanism Ca for moving the first switching pin 73 back and forth in the directions perpendicularly to the axial directions of the intake switching drive shaft 71 while being guided by the cam profile of the cam surface 71C upon axial movement of the intake switching drive shaft 71.

As depicted in FIG. 7, the first switching pin 73 and the second switching pin 74 extend diametrically through the common elongate hole 71a in the intake switching drive shaft 71 and are arrayed parallel to each other.

In FIG. 7, the right recessed faces 71Cv of the cam surface 71C of the intake switching drive shaft 71 have their centers positioned on the first switching pin 73, whose conical end face 73bt is held in abutment against the right recessed faces 71Cv, placing the first switching pin 73 in an advanced position, while the conical end face 74bt of the proximal cylindrical column 74b of the second switching pin 74 is held in abutment against the flat faces 71Cp of the cam surface 71C, placing the second switching pin 74 in a retracted position.

When the intake switching drive shaft 71 moves axially to the right, the conical end face 73bt of the first switching pin 73 slides up from the centers of the right recessed faces 71Cv along slanting surfaces thereof while being retracted onto the flat faces 71Cp. On the other hand, the conical end face 74bt of the second switching pin 74 slides down from the flat surfaces 71Cp along slanting surfaces of the left

recessed faces 71Cv while being advanced onto the centers of the left recessed faces 71Cv.

In this manner, the first switching pin 73 and the second switching pin 74 are alternatively advanced and retracted upon axial movement of the intake switching drive shaft 71.

Although not depicted, the tubular rod 3B, in which the exhaust switching drive shaft 81 is axially slidably fitted, also has two left and right cylindrical bosses 3Bs that are adjacent to each other in the leftward and rightward directions, disposed at respective positions corresponding to and projecting toward the lead groove tube 53D of each of the exhaust cam carriers 53. The cylindrical bosses 3Bs have respective bores defined therein which extend through the tubular rod 3B, and a first switching pin 83 and a second switching pin 84 are slidably fitted individually in the bores in the left and right cylindrical bosses 3Bs. The first switching pin 83 and the second switching pin 84 extend diametrically through a common elongate hole 81a in the exhaust switching drive shaft 81 and are arrayed parallel to each other (see FIGS. 5 and 6).

The exhaust switching drive shaft 81 and the first and second switching pins 83 and 84 jointly make up a linear-motion cam mechanism Cb for moving the first and second switching pins 83 and 84 back and forth in the directions perpendicularly to the axial directions of the exhaust switching drive shaft 81 while being guided by the cam profile of a cam surface 81C (see FIG. 8), which is formed on an open end face of the elongate hole 81a and is of the same cam profile as the cam surface 71C, upon axial movement of the exhaust switching drive shaft 81.

As depicted in FIG. 5, the exhaust switching drive shaft 81 and the first and second switching pins 83 and 84 in the cylindrical bosses 3Bs are disposed so as to be at least partly superposed on axial extensions of the right four stud bolts 7 on the front side (exhaust side), of all the (ten) stud bolts 7 by which the cylinder block 2 and the cylinder head 3 are stacked on and fastened to the crankcase 1.

Referring to FIGS. 5 and 6, an intake hydraulic pressure actuator 77 for axially moving the intake switching drive shaft 71 is mounted on the left side wall 3Lh of the upper cylinder head member 3U and projects into the valve operating compartment 3d, and an exhaust hydraulic pressure actuator 87 for axially moving the exhaust switching drive shaft 81 is mounted on the left side wall 3Lh of the upper cylinder head member 3U and projects into the valve operating compartment 3d. The exhaust hydraulic pressure actuator 87 is disposed forwardly of the intake hydraulic pressure actuator 77 in side-by-side relationship.

The intake hydraulic pressure actuator 77 and the exhaust hydraulic pressure actuator 87 are formed integrally with the upper cylinder head member 3U.

As depicted in FIG. 5, the intake hydraulic pressure actuator 77 and the exhaust hydraulic pressure actuator 87 are disposed so as to be at least partly superposed on axial extensions of the leftmost two stud bolts 7 of all the (ten) stud bolts 7 by which the cylinder block 2 and the cylinder head 3 are stacked on and fastened to the crankcase 1.

As depicted in FIGS. 8 and 9, the intake hydraulic pressure actuator 77 includes an intake actuator housing 78 having an inner housing chamber defined therein as a round hole and an intake actuator drive body 79 having a bottomed hollow cylindrical shape fitted in the inner housing chamber for reciprocating sliding movement in the axial directions (leftward and rightward directions) of the intake switching drive shaft 71. The intake switching drive shaft 71 has a left end securely fitted in the intake actuator drive body 79 for movement therewith.

The inner housing chamber in the intake actuator housing 78 has a left opening closed by a lid 76 and is divided into a left high-speed hydraulic pressure chamber 78_H and a right low-speed hydraulic pressure chamber 78_L by the intake actuator drive body 79.

Likewise, the exhaust hydraulic pressure actuator 87 includes an exhaust actuator housing 88 having an inner housing chamber defined therein as a round hole and an exhaust actuator drive body 89 having a bottomed hollow cylindrical shape fitted in the inner housing chamber for reciprocating sliding movement in the axial directions (leftward and rightward directions) of the exhaust switching drive shaft 81. The exhaust switching drive shaft 81 has a left end securely fitted in the exhaust actuator drive body 89 for movement therewith.

The inner housing chamber in the exhaust actuator housing 88 has a left opening closed by a lid 86 and is divided into a left high-speed hydraulic pressure chamber 88_H and a right low-speed hydraulic pressure chamber 88_L by the exhaust actuator drive body 89.

Still referring to FIGS. 8 and 9, the left side wall 3Lh of the upper cylinder head member 3U has a high-speed oil supply and discharge channel 90_H defined therein that provides fluid communication between the high-speed hydraulic pressure chamber 78_H of the intake hydraulic pressure actuator 77 and the high-speed hydraulic pressure chamber 88_H of the exhaust hydraulic pressure actuator 87. The left side wall 3Lh of the upper cylinder head member 3U also has a low-speed oil supply and discharge channel 90_L defined therein that provides fluid communication between the low-speed hydraulic pressure chamber 78_L of the intake hydraulic pressure actuator 77 and the low-speed hydraulic pressure chamber 88_L of the exhaust hydraulic pressure actuator 87.

The high-speed oil supply and discharge channel 90_H extends forwardly through the high-speed hydraulic pressure chamber 88_H of the exhaust hydraulic pressure actuator 87 and, as shown in FIG. 10, is open at a left end mating surface 3FL on the left end of a front surface of the front side wall 3Fr of the upper cylinder head member 3U. The low-speed oil supply and discharge channel 90_L extends forwardly through the low-speed hydraulic pressure chamber 88_L of the exhaust hydraulic pressure actuator 87 and, as shown in FIG. 10, is open at the left end mating surface 3FL of the front side wall 3Fr.

The intake actuator drive body 79, shaped as a bottomed hollow cylinder, of the intake hydraulic pressure actuator 77 has an axially elongate hole 79h defined in a hollow cylindrical portion thereof that faces the high-speed oil supply and discharge channel 90_H. Consequently, even when the intake actuator drive body 79 is axially moved in the inner housing chamber, the fluid communication port of the high-speed oil supply and discharge channel 90_H which is defined in the intake actuator housing 78 and open into the inner housing chamber, faces the axially elongate hole 79h in the hollow cylindrical portion of the intake actuator drive body 79 at all times, always keeping the high-speed oil supply and discharge channel 90_H and the high-speed hydraulic pressure chamber 78_H in fluid communication with each other.

The exhaust actuator drive body 89, shaped as a bottomed hollow cylinder, of the exhaust hydraulic pressure actuator 87 has two axially elongate holes 89h defined in hollow cylindrical portions thereof that face the high-speed oil supply and discharge channel 90_H. Consequently, even when the exhaust actuator drive body 89 is axially moved in the inner housing chamber, the fluid communication port of the high-speed oil supply and discharge channel 90_H which is

defined in the exhaust actuator housing 88 and open into the inner housing chamber, faces the axially elongate holes 89h in the hollow cylindrical portions of the exhaust actuator drive body 89 at all times, always keeping the high-speed oil supply and discharge channel 90_H and the high-speed hydraulic pressure chamber 88_H in fluid communication with each other.

The low-speed oil supply and discharge channel 90_L is held in fluid communication with the low-speed hydraulic pressure chamber 78_L of the intake hydraulic pressure actuator 77 and the low-speed hydraulic pressure chamber 88_L of the exhaust hydraulic pressure actuator 87 at all times even when the intake actuator drive body 79 of the intake hydraulic pressure actuator 77 and the exhaust actuator drive body 89 of the exhaust hydraulic pressure actuator 87 are axially moved to the left or right.

FIG. 10 depicts the left end mating surface 3FL on the left end of the front surface of the front side wall 3Fr of the upper cylinder head member 3U. As shown in FIG. 10, the high-speed oil supply and discharge channel 90_H and the low-speed oil supply and discharge channel 90_L are open at the left end mating surface 3FL, and oblong grooves 90_{HH} and 90_{LL} are defined in the left end mating surface 3FL and extend obliquely upward from the openings of the high-speed oil supply and discharge channel 90_H and the low-speed oil supply and discharge channel 90_L.

A linear solenoid valve 91 (see FIG. 9) is mounted on the left end mating surface 3FL on the left end of the front surface of the front side wall 3Fr of the upper cylinder head member 3U.

As depicted in FIGS. 8 and 9, the linear solenoid valve 91 includes an electromagnetic solenoid 92 including a plunger 92p movable in an electromagnetic coil 92c, and a sleeve 93 connected to and extending axially from the electromagnetic solenoid 92.

A spool valve 94 is slidably inserted in the sleeve 93 and normally biased by a spring 95 to abut coaxially against the plunger 92p.

The linear solenoid valve 91 is mounted on the left end mating surface 3FL on the left end of a front surface of the front side wall 3Fr of the upper cylinder head member 3U such that the spool valve 94 which is coaxial with the plunger 92p of the electromagnetic solenoid 92 is oriented horizontally in the leftward and rightward directions (see FIGS. 2, 3, and 5).

As depicted in FIGS. 8 and 9, the spool valve 94 of the linear solenoid valve 91 is oriented in the leftward and rightward directions parallel to the intake switching drive shaft 71 and the exhaust switching drive shaft 81, and is movable selectively in the leftward and rightward directions.

When the electromagnetic coil 92c is energized, the plunger 92p is axially shifted in the leftward direction under electromagnetic forces, pushing the spool valve 94 in the sleeve 93 to the left (LH) against the bias of the spring 95 (see FIG. 9). When the electromagnetic coil 92c is de-energized, the plunger 92p is released and pushed back in the rightward direction by the spool valve 94 which is retracted to the right (RH) under the bias of the spring 95 (see FIG. 8).

The sleeve 93 has a central hydraulic pressure supply port 93_H defined therein, a high-speed supply and discharge port 93_H and a low-speed supply and discharge port 93_L defined therein that are positioned individually on both sides of the central hydraulic pressure supply port 93_H, and a pair of drain ports 93_D defined therein that are positioned individually on both sides of the high-speed supply and discharge port 93_H and the low-speed supply and discharge port 93_L.

The spool valve 94 that is axially slidable in the sleeve 93 has a central hydraulic pressure supply groove 94_I defined therein and a pair of drain grooves 94_D defined therein that are positioned axially side by side individually on both sides of the central hydraulic pressure supply groove 94_I with respective lands interposed therebetween.

In FIGS. 8 and 9, the sleeve 93 of the linear solenoid valve 91 is schematically illustrated.

FIG. 11 depicts the linear solenoid valve 91 in realistic representation. The sleeve 93 has a mating surface 93R as a rear side surface thereof, and the central hydraulic pressure supply port 93_I, the high-speed supply and discharge port 93_H, the low-speed supply and discharge port 93_L, and the drain ports 93_D are open at the mating surface 93R.

The mating surface 93R as a rear side surface of the sleeve 93 of the linear solenoid valve 91 mates with the left end mating surface 3FL (see FIG. 10) on the left end of the front surface of the front side wall 3Fr of the upper cylinder head member 3U, so that the linear solenoid valve 91 is mounted on the upper cylinder head member 3U.

The left end mating surface 3FL of the front side wall 3Fr of the upper cylinder head member 3U depicted in FIG. 10 has respective openings defined therein of a hydraulic pressure supply channel 90_I, the oblong groove 90_{HH} connected to the high-speed oil supply and discharge channel 90_H, the oblong groove 90_{LL} connected to the low-speed oil supply and discharge channel 90_L, and a pair of drain oil channels 90_D in facing relation to respective openings of the central hydraulic pressure supply port 93_I, the high-speed supply and discharge port 93_H, the low-speed supply and discharge port 93_L, and the drain ports 93_D in the sleeve 93.

In FIG. 8, the electromagnetic solenoid 92 of the linear solenoid valve 91 is de-energized, and the spool valve 94 is retracted to the right (RH) under the bias of the spring 95. Therefore, oil under pressure that has flowed into the central hydraulic pressure supply port 93_I of the sleeve 93 flows through the central hydraulic pressure supply groove 94_I into the low-speed supply and discharge port 93_L, from which the oil flows through the oblong groove 90_{LL} into the low-speed oil supply and discharge channel 90_L in the left side wall 3Lh of the upper cylinder head member 3U and is supplied to the low-speed hydraulic pressure chamber 88_L of the exhaust hydraulic pressure actuator 87 and then via the low-speed hydraulic pressure chamber 88_L to the low-speed hydraulic pressure chamber 78_L of the intake hydraulic pressure actuator 77, pushing the intake actuator drive body 79 of the intake hydraulic pressure actuator 77 and the exhaust actuator drive body 89 of the exhaust hydraulic pressure actuator 87 to the left (LH).

Since the actuator drive bodies 79 and 89 of the intake and exhaust hydraulic pressure actuators 77 and 87 are moved to the left (LH), oil under pressure flows out of the high-speed hydraulic pressure chambers 78_H and 88_H of the intake and exhaust hydraulic pressure actuators 77 and 87 into the high-speed oil supply and discharge channel 90_H, from which the oil flows through the oblong groove 90_{HH} into the high-speed supply and discharge port 93_H in the sleeve 93 of the linear solenoid valve 91, and is then discharged via the drain groove 94_D from the drain port 93_D into the drain oil channel 90_D.

When the electromagnetic solenoid 92 of the linear solenoid valve 91 is de-energized as described above, as depicted in FIG. 8, oil under pressure is supplied to the low-speed hydraulic pressure chambers 78_L and 88_L of the intake and exhaust hydraulic pressure actuators 77 and 87, and oil under pressure flows out of the high-speed hydraulic pressure chambers 78_H and 88_H thereof, moving the actuator

drive bodies 79 and 89 of the intake and exhaust hydraulic pressure actuators 77 and 87 simultaneously to the left (LH), thereby moving the intake switching drive shaft 71 and the exhaust switching drive shaft 81 whose left ends are securely fitted respectively in the actuator drive bodies 79 and 89 also simultaneously to the left (LH).

When the electromagnetic solenoid 92 of the linear solenoid valve 91 is energized, as depicted in FIG. 9, the spool valve 94 projects to the left (LH) against the bias of the spring 95, oil under pressure that has flowed into the central hydraulic pressure supply port 93_I of the sleeve 93 flows through the central hydraulic pressure supply groove 94_I into the high-speed supply and discharge port 93_H, from which the oil flows through the oblong groove 90_{HH} into the high-speed oil supply and discharge channel 90_H in the left side wall 3Lh of the upper cylinder head member 3U and is supplied to the high-speed hydraulic pressure chamber 88_H of the exhaust hydraulic pressure actuator 87 and then via the high-speed hydraulic pressure chamber 88_H to the high-speed hydraulic pressure chamber 78_H of the intake hydraulic pressure actuator 77, pushing the intake actuator drive body 79 of the intake hydraulic pressure actuator 77 and the exhaust actuator drive body 89 of the exhaust hydraulic pressure actuator 87 to the right (RH).

Oil under pressure flows out of the low-speed hydraulic pressure chambers 78_L and 88_L of the intake and exhaust hydraulic pressure actuators 77 and 87 into the low-speed oil supply and discharge channel 90_L, from which the oil flows through the oblong groove 90_{LL} into the low-speed supply and discharge port 93_L, in the sleeve 93 of the linear solenoid valve 91, and is then discharged via the drain groove 94_D from the drain port 93_D into the drain oil channel 90_D.

When the electromagnetic solenoid 92 of the linear solenoid valve 91 is energized as described above, as depicted in FIG. 9, oil under pressure is supplied to the high-speed hydraulic pressure chambers 78_H and 88_H of the intake and exhaust hydraulic pressure actuators 77 and 87, and oil under pressure flows out of the low-speed hydraulic pressure chambers 78_L and 88_L thereof, moving the actuator drive bodies 79 and 89 of the intake and exhaust hydraulic pressure actuators 77 and 87 simultaneously to the right (RH), thereby moving the intake switching drive shaft 71 and the exhaust switching drive shaft 81 whose left ends are securely fitted respectively in the actuator drive bodies 79 and 89 also simultaneously to the right (RH).

When the electromagnetic solenoid 92 of the linear solenoid valve 91 is de-energized, moving the intake switching drive shaft 71 and the exhaust switching drive shaft 81 to the left (LH), as described above, the first switching pin 73 of each linear-motion cam mechanism Ca is in the advanced position where it abuts against the recessed face 71Cv of the cam surface 71C of the intake switching drive shaft 71 and the second switching pin 74 of each linear-motion cam mechanism Ca is in the retracted position where it abuts against the flat face 71Cp of the cam surface 71C in the intake cam switching mechanism 70 depicted in FIG. 12.

The advanced first switching pin 73 engages in the annular lead groove 44c of the lead groove tube 43D of the intake cam carrier 43 that has moved to the right, whereupon the intake cam carrier 43 is kept in a predetermined right position rather than moving axially.

While the intake cam carrier 43 is in the predetermined right position (low-speed position), as depicted in FIG. 12, the low-speed cam lobe 43B acts on the intake rocker arm 72, causing the intake valve 41 to operate according to low-speed valve operating characteristics set by the cam profile of the low-speed cam lobe 43B.

In other words, the internal combustion engine E operates in a low-speed mode.

When the electromagnetic solenoid 92 of the linear solenoid valve 91 is then energized, moving the intake switching drive shaft 71 to the right (RH), as depicted in FIG. 13, the conical end face 73bt of the first switching pin 73 slides from the centers of the right recessed faces 71Cv up the slanting surfaces thereof as it is retracted onto the flat faces 71Cp, and the conical end face 74bt of the second switching pin 74 slides from the flat surfaces 71Cp down the slanting surfaces of the left recessed faces 71Cv as it is advanced onto the centers of the left recessed faces 71Cv.

The retracted first switching pin 73 disengages from the annular lead groove 44c in the intake cam carrier 43, and the advanced second switching pin 74 engages into the left shift lead groove 44l. Therefore, the intake cam carrier 43 is moved axially to the left while rotating and being guided by the left shift lead groove 44l. As depicted in FIG. 13, the second switching pin 74 shifts from the left shift lead groove 44l into the annular lead groove 44c, keeping the intake cam carrier 43 in a predetermined left position.

While the intake cam carrier 43 is in the predetermined left position (high-speed position), as depicted in FIG. 13, the high-speed cam lobe 43A acts on the intake rocker arm 72, causing the intake valve 41 to operate according to high-speed valve operating characteristics set by the cam profile of the high-speed cam lobe 43A.

In other words, the internal combustion engine E operates in a high-speed mode.

When the intake switching drive shaft 71 is moved to the left while the internal combustion engine E is operating in the high-speed mode, the second switching pin 74 is retracted out of the annular lead groove 44c, and the first switching pin 73 is advanced into the right shift lead groove 44r. The intake cam carrier 43 is guided by the right shift lead groove 44r to move axially to the right while rotating. As depicted in FIG. 12, the intake cam carrier 43 is now kept in the predetermined right position (low-speed position), and the internal combustion engine E operates in the low-speed mode with the low-speed cam lobe 43B acting on the intake rocker arm 72.

The exhaust cam switching mechanism 80 also operates depending on movement of the exhaust switching drive shaft 81 in the same manner as the intake cam switching mechanism 70 operates depending on movement of the intake switching drive shaft 71 as the electromagnetic solenoid 92 of the linear solenoid valve 91 is energized and de-energized as described above.

The internal combustion engine E according to the embodiment of the present invention described in detail above offers the following advantages.

As depicted in FIGS. 2 and 3, since the linear solenoid valve 91 is mounted on the front surface of the cylinder head 3 standing on the crankcase 1, the linear solenoid valve 91 does not protrude laterally in the leftward and rightward directions of the cylinder head 3, thereby preventing the internal combustion engine E from increasing its width in the leftward and rightward directions.

Furthermore, as the linear solenoid valve 91 is mounted on the left end mating surface 3FL on the left end in the leftward and rightward directions across the vehicle width of the front surface of the cylinder head 3, peripheral parts of the internal combustion engine E can be placed closely to the front surface of the cylinder head 3, using a wide central space, except the linear solenoid valve 91, on the front surface of the cylinder head 3. The peripheral area of the internal combustion engine is thus rendered compact, reduc-

ing the length of the vehicle in the forward and rearward directions to make the vehicle small in size.

Inasmuch as the linear solenoid valve 91 is mounted on the upper cylinder head member 3U, the hydraulic liquid supply and discharge channels 90_H and 90_L that provide fluid communication between the intake hydraulic pressure actuator 77 and the exhaust hydraulic pressure actuator 87 that are provided in the upper cylinder head member 3U can be shortened.

As depicted in FIG. 5, the intake hydraulic pressure actuator 77 and the exhaust hydraulic pressure actuator 87 are integrally formed with the upper cylinder head member 3U. As depicted in FIGS. 10 and 11, the mating surface 93R which has the respective openings of the central hydraulic pressure supply port 93_P, the high-speed supply and discharge port 93_H, the low-speed supply and discharge port 93_L, and the drain ports 93_D of the linear solenoid valve 91 mates with the left end mating surface 3FL which has the respective openings of the hydraulic pressure supply channel 90_P, the oblong groove 90_{HH} connected to the high-speed oil supply and discharge channel 90_H, the oblong groove 90_{LL} connected to the low-speed oil supply and discharge channel 90_L, and the drain oil channels 90_D of the upper cylinder head member 3U, so that the linear solenoid valve 91 is mounted on the upper cylinder head member 3U. Therefore, the hydraulic pressure channels in the linear solenoid valve 91 and the hydraulic pressure channels in the intake hydraulic pressure actuator 77 and the exhaust hydraulic pressure actuator 87 that are provided in the upper cylinder head member 3U are coupled directly to each other, and hence can be short without the need for separate joint pipes.

As depicted in FIGS. 4 and 5, since the directions in which the plunger 92p and the spool valve 94 of the electromagnetic solenoid 92 of the linear solenoid valve 91 are moved are perpendicular to the cylinder axes Lc, the linear solenoid valve 91 is not susceptible to vibrations caused by the internal combustion engine E while in operation, and can operate in an exact manner.

As shown in FIG. 5, the intake hydraulic pressure actuator 77 and the exhaust hydraulic pressure actuator 87 are provided respectively on the left ends of the intake switching drive shaft 71 and the exhaust switching drive shaft 81, and the linear solenoid valve 91 is disposed on the same left side in the leftward and rightward directions across the vehicle width as the intake hydraulic pressure actuator 77 and the exhaust hydraulic pressure actuator 87. Consequently, the linear solenoid valve 91, the intake hydraulic pressure actuator 77 and the exhaust hydraulic pressure actuator 87 are disposed closely to each other, making it possible to shorten the hydraulic liquid supply and discharge channels 90_H and 90_L that provide fluid communication therebetween. Therefore, the internal combustion engine E is prevented from being large in size.

As depicted in FIG. 5, the linear solenoid valve 91 is disposed opposite the cam chain compartment 3c housing the cam chain 66 therein in the axial directions of the intake camshaft 42 and the exhaust camshaft 52. Therefore, the linear solenoid valve 91 is prevented from further protruding on the side wall where the cam chain compartment 3c is defined. Consequently, the internal combustion engine E is prevented from being large in size.

As depicted in FIG. 4, the cylinder head 3, which is separable along the cylinder axes, includes the lower cylinder head member (first cylinder head member) 3L mounted on the cylinder block 2 and the upper cylinder head member (second cylinder head member) 3U mounted on the lower cylinder head member 3L. The intake valve 41 and the

exhaust valve 51 are supported on the lower cylinder head member 3L, whereas the bearings 3vv for the intake cam-shaft 42 and the exhaust cam-shaft 52 are provided on the upper cylinder head member 3U and the intake hydraulic pressure actuator 77 and the exhaust hydraulic pressure actuator 87 are supported on the upper cylinder head member 3U. The linear solenoid valve 91 is provided in the upper cylinder head member 3U.

Therefore, the intake cam-shaft 42, the exhaust cam-shaft 52, the intake cam switching mechanism 70, the exhaust cam switching mechanism 80, the intake hydraulic pressure actuator 77, and the exhaust hydraulic pressure actuator 87, other than the intake valve 41 and the exhaust valve 51 that are supported on the lower cylinder head member 3L, are provided on the separate upper cylinder head member 3U. The lower cylinder head member 3L and the upper cylinder head member 3U are thus simplified in structure, and can be manufactured with ease. Furthermore, as the linear solenoid valve 91 is provided in the upper cylinder head member 3U, the high-speed hydraulic liquid supply and discharge channel 90_H and the low-speed hydraulic liquid supply and discharge channel 90_L that provide fluid communication between the linear solenoid valve 91 and the intake hydraulic pressure actuator 77 and the exhaust hydraulic pressure actuator 87 can be short and constructed with ease.

As depicted in FIGS. 2 and 3, the radiator 130 which is curved to project rearward is disposed along the front surface of the cylinder head 3, and the linear solenoid valve 91 and the radiator 130 are disposed so as to be partly superposed on each other as viewed in side elevation in the widthwise directions of the vehicle. Consequently, the radiator 130 that is curved to project rearward can be placed as closely to the cylinder head 3 as possible out of interference with the solenoid valve 91 mounted on the left end mating surface 3FL on the left end in the leftward and rightward directions across the vehicle width of the front surface of the upper cylinder head member 3U. The radiator 130 and the internal combustion engine E that are disposed in front and rear positions can be disposed in a compact layout, making it possible to minimize the length of the vehicle in the forward and rearward directions.

Although the internal combustion engine according to the embodiment of the present invention has been described above, the present invention is not limited to the above embodiment, but may be reduced to practice according to various embodiments within the scope of the gist of the invention.

According to the present embodiment, one solenoid valve operates two actuators. The present invention is not limited to such a configuration, but two actuators may independently be operated by two solenoid valves.

According to such a modification, the two solenoid valves may be disposed together forward of the internal combustion engine or may be disposed individually forward and rearward of the internal combustion engine.

The vehicle according to the present invention is not limited to the saddle-type motorcycle 1 according to the present embodiment, but may be any of various saddle-type vehicles including scooter-type vehicles, three- and four-wheeled buggies, etc. insofar as it meets the requirements of claim 1.

 The invention claimed is:
 1. An internal combustion engine for use on a saddle-type vehicle, including a cylinder block and a cylinder head stacked on and integrally fastened to a crankcase, the internal combustion engine having a variable valve operating apparatus comprising:

23

a camshaft rotatably mounted in the cylinder head and oriented in leftward and rightward directions across a vehicle width; a cam carrier in the form of a hollow cylindrical member relatively non-rotatably and axially slidably fitted over the camshaft, the cam carrier including, on an outer circumferential surface thereof, a plurality of cam lobes having different cam profiles and disposed axially adjacent to each other; and a cam switching mechanism for axially moving the cam carrier to switch the cam lobes to act on an engine valve, wherein the cam switching mechanism includes: a lead groove formed in the outer circumferential surface of the cam carrier and extending fully circumferentially therearound; a switching pin capable of being advanced to engage in and retracted to disengage from the lead groove; a switching drive shaft disposed parallel to the camshaft to be movable longitudinally thereof so as to cooperate with the switching pin to constitute a cam mechanism for advancing and retracting movements of the switching pin, in such a manner that the advancing movement causes the switching pin to engage in the lead groove so as to axially move the cam carrier while rotating, to switch the cam lobes to act on the engine valve; a hydraulic pressure actuator for longitudinally moving the switching drive shaft; and a solenoid valve for switching hydraulic pressure acting on the hydraulic pressure actuator, the solenoid valve being positioned on one of left and right ends in the leftward and rightward directions across the vehicle width, of one of front and rear surfaces of the cylinder head.

2. The internal combustion engine according to claim 1, wherein the solenoid valve is disposed on the front surface of the cylinder head.

3. The internal combustion engine according to claim 2, further comprising a radiator shaped to curve to project rearward and disposed along the front surface of the cylinder head;

wherein the solenoid valve and the radiator are partly superposed on each other as viewed in side elevation in widthwise directions of the saddle-type vehicle.

4. The internal combustion engine according to claim 2, wherein:

the hydraulic pressure actuator is integrally formed with the cylinder head; the cylinder head includes a mating surface having openings of hydraulic pressure channels defined therein; and the solenoid valve has a mating surface with openings of hydraulic pressure ports defined therein, the mating surface of the solenoid valve mating with the mating surface of the cylinder head, so that the solenoid valve is mounted on the cylinder head.

5. The internal combustion engine according to claim 2, wherein the solenoid valve includes an electromagnetic solenoid having a plunger and a spool valve operable with the plunger, the solenoid valve being mounted on the cylinder head in such a posture that the plunger is linearly movable together with the spool valve in directions perpendicular to axial directions of a cylinder defined in the cylinder block.

6. The internal combustion engine according to claim 2, wherein:

24

the hydraulic pressure actuator is mounted on one of left and right ends of the switching drive shaft; and the solenoid valve is disposed on the same side in the leftward and rightward directions across the vehicle width as the hydraulic pressure actuator.

7. The internal combustion engine according to claim 2, wherein:

the camshaft is rotatable by drive power transmitted from the internal combustion engine through a cam chain; and

the solenoid valve is disposed opposite a cam chain compartment housing the cam chain therein, in axial directions of the camshaft.

8. The internal combustion engine according to claim 2, wherein:

the cylinder head is separable in axial directions of the cylinder in the cylinder block into a first cylinder head member mounted on the cylinder block and a second cylinder head member mounted on the first cylinder head member;

the engine valve is supported on the first cylinder head member;

the second cylinder head member has bearings by which the camshaft is rotatably supported, the hydraulic pressure actuator being supported on the second cylinder head member; and

the solenoid valve is provided in the second cylinder head member.

9. The internal combustion engine according to claim 1, wherein:

the hydraulic pressure actuator is integrally formed with the cylinder head;

the cylinder head includes a mating surface having openings of hydraulic pressure channels defined therein; and the solenoid valve has a mating surface with openings of hydraulic pressure ports defined therein, the mating surface of the solenoid valve mating with the mating surface of the cylinder head, so that the solenoid valve is mounted on the cylinder head.

10. The internal combustion engine according to claim 9, wherein the solenoid valve includes an electromagnetic solenoid having a plunger and a spool valve operable with the plunger, the solenoid valve being mounted on the cylinder head in such a posture that the plunger is linearly movable together with the spool valve in directions perpendicular to axial directions of a cylinder defined in the cylinder block.

11. The internal combustion engine according to claim 9, wherein:

the hydraulic pressure actuator is mounted on one of left and right ends of the switching drive shaft; and

the solenoid valve is disposed on the same side in the leftward and rightward directions across the vehicle width as the hydraulic pressure actuator.

12. The internal combustion engine according to claim 9, wherein:

the camshaft is rotatable by drive power transmitted from the internal combustion engine through a cam chain; and

the solenoid valve is disposed opposite a cam chain compartment housing the cam chain therein, in axial directions of the camshaft.

13. The internal combustion engine according to claim 9, wherein:

the cylinder head is separable in axial directions of the cylinder in the cylinder block into a first cylinder head

25

member mounted on the cylinder block and a second cylinder head member mounted on the first cylinder head member;

the engine valve is supported on the first cylinder head member;

the second cylinder head member has bearings by which the camshaft is rotatably supported, the hydraulic pressure actuator being supported on the second cylinder head member; and

the solenoid valve is provided in the second cylinder head member.

14. The internal combustion engine according to claim 1, wherein the solenoid valve includes an electromagnetic solenoid having a plunger and a spool valve operable with the plunger, the solenoid valve being mounted on the cylinder head in such a posture that the plunger is linearly movable together with the spool valve in directions perpendicular to axial directions of a cylinder defined in the cylinder block.

15. The internal combustion engine according to claim 14, wherein:

the hydraulic pressure actuator is mounted on one of left and right ends of the switching drive shaft; and

the solenoid valve is disposed on the same side in the leftward and rightward directions across the vehicle width as the hydraulic pressure actuator.

16. The internal combustion engine according to claim 14, wherein:

the camshaft is rotatable by drive power transmitted from the internal combustion engine through a cam chain; and

the solenoid valve is disposed opposite a cam chain compartment housing the cam chain therein, in axial directions of the camshaft.

26

17. The internal combustion engine according to claim 1, wherein:

the hydraulic pressure actuator is mounted on one of left and right ends of the switching drive shaft; and

the solenoid valve is disposed on the same side in the leftward and rightward directions across the vehicle width as the hydraulic pressure actuator.

18. The internal combustion engine according to claim 17, wherein:

the camshaft is rotatable by drive power transmitted from the internal combustion engine through a cam chain; and

the solenoid valve is disposed opposite a cam chain compartment housing the cam chain therein, in axial directions of the camshaft.

19. The internal combustion engine according to claim 1, wherein:

the camshaft is rotatable by drive power transmitted from the internal combustion engine through a cam chain; and

the solenoid valve is disposed opposite a cam chain compartment housing the cam chain therein, in axial directions of the camshaft.

20. The internal combustion engine according to claim 1, wherein:

the cylinder head is separable in axial directions of the cylinder in the cylinder block into a first cylinder head member mounted on the cylinder block and a second cylinder head member mounted on the first cylinder head member;

the engine valve is supported on the first cylinder head member;

the second cylinder head member has bearings by which the camshaft is rotatably supported, the hydraulic pressure actuator being supported on the second cylinder head member; and

the solenoid valve is provided in the second cylinder head member.
